LEVELER

Harry N. Peavey, Aberdeen, Md., assignor, by
mesne assignments, to Levelor Corporation, a
corporation of New York

Application February 12, 1946, Serial No. 647,095

6 Claims. (Cl. 45—139)

1

This invention relates to improvements in devices for leveling articles of furniture, etc.

A further object of this invention is the provision of a leveling device presenting characteristics somewhat similar to those of the leveling device set forth in a co-pending application, Serial Number 605,601, filed July 17, 1945, in the United States Patent Office, and embodying improvements thereover.

A further object of this invention is the provision of a relatively simple and efficient type of leveling device which may be constructed relatively cheap from synthetic plastic or other materials, and which embodies an efficient and compact arrangement for locking the desired adjustment; all parts being readily accessible and easily operated for varying the adjustment as desired.

Other objects and advantages of the invention will be apparent from the following detailed description.

In the accompanying drawing, forming a part of this specification and wherein similar reference characters designate corresponding parts throughout the several views—

Figure 1 is a side elevation of the leveling device showing its application upon the leg of some article to be leveled; the leg being shown in cross section.

Figure 2 is a vertical sectional view taken through the improved leveling device showing the parts in position for locked leveling adjustment.

Figure 3 is a vertical sectional view similar to Figure 2, but with the parts in position to permit relative adjustment thereof.

Figure 4 is a view, partly in top elevation and partly in cross section showing details of the improved leveling device.

In the drawing, wherein for the purpose of illustration is shown only a preferred embodiment of the invention, the letter A may generally designate the improved leveling device which may be utilized for leveling furniture or for adjusting the height of such articles as desks, tables, machinery, etc. This consists of a tread providing cap or base 10; an expandible locking sleeve or bushing 11; an article attaching plug 12, and a screw 13 for connecting the entire leveling device to some leg or other part 15 of an article to be leveled.

The parts 10, 11 and 12 may be made of any desired material, although preferably they are constructed of some hard plastic, such as synthetic resin. These parts may be colored to suit, or may be transparent or translucent.

The attaching plug 12 is provided with a cen-

2

tral passageway 20 therethrough. It is of general cylindrical formation and at the lower margin thereof it is provided with an annular rounded flange or cam extension 21 which is adapted to be used in expanding the split sleeve or bushing 11, as will be subsequently described. This plug is countersunk at 23 inwardly from the lower surface thereof wherein the head 24 of the screw 13 is adapted to be received; the smooth portion of the shank of the screw 13 extending through passageway 20 and at its screw threaded end 26 projecting upwardly for attaching upon the article to be leveled. The upper surface of the plug 12 is provided with a plurality of pointed projections 30 integral therewith which bite into the leg 15, as shown in Figure 1, and serve to prevent rotation of the plug relative to the leg 15.

The sleeve or bushing 11 is externally threaded at 35 and the lower skirt portion thereof is provided with vertical slots or splits 36 extending substantially half way of the height of this bushing and opening both externally and internally. In this slotted skirt portion the bushing 11 is annularly recessed at 38; and the surfacing defining this recess 38 preferably normally converges downwardly to the slotted bottom edge 40 of the bushing. The annular flange or cam extension 21 of the plug is adapted to seat in the groove 38. In normal position, shown in Figure 3, the bushing cam flange 21 will not expand the slotted skirt of the bushing, but as the sleeve or bushing is moved along the plug 12 the cam flange 21 will ride along the convergent surface of the groove 38 and laterally and radially expand the slotted skirt of the bushing, as will be noted from Figure 2. The plug 12 is slidably received within the passageway 41 of the bushing 11, and to prevent relative rotation of the parts 11 and 12 the plug 12 may be provided with lateral recesses 45 opening on the top surface 46 of the plug wherein are received the radially projecting lugs 48 formed integral with the sleeve or bushing 11 internally thereof, upon the upper unsplit portion of the bushing.

The tread cap 10 includes the annular body portion 60 internally screw threaded at 61, and having a bottom wall 62 provided with a central opening 63 therein.

The parts 10, 11 and 12 are relatively shallow in depth; the adjustment being secured by threading the bushing part 11 in the tread cap 10.

In assemblage upon an article, the screw, of course, attaches the plug 12 to the leg 15, and the bushing 11 is held upon the plug in the position

shown in Figure 3; the tread cap being threaded upon the bushing.

In order to secure a leveling adjustment it is merely necessary to rotate the tread cap upon the bushing, to a position such as shown in Figures 1 and 2, and merely by pushing the adjusted parts 10 and 11 upwardly the cam flange 21 will expand the split portion of the bushing to lock its threads with the threads of the cap and this will prevent any accidental relative rotation of the parts 10 and 11. It will be noted that the distance which the bushing 11 rides along the plug to secure the expansion of the bushing is exaggerated, in order to clearly bring out the relative play of these parts. In actual use the relative movement of the bushing along the plug to lock the adjustment of the parts 10 and 11 is very small, and insufficient to disrupt a desired adjustment.

It will be noted that the weight of the article supported by the leveler normally tends to lock the adjustment by forcing the plug downwardly for expanding the sleeve 12. When it is desired to readjust the parts it is merely necessary to pull the locked parts 10 and 11 downwardly and release the cam action of the flange 21 upon the sleeve or bushing 12. The parts 10 and 11 may then be relatively rotated to vary the adjustment.

It will be noted that the opening 63 gives ready access to the head of the screw so that the latter can be removed from the leg 15 and the leveler disconnected. If desired, this opening may be made slightly smaller than the screw head, so that the screw cannot become detached from the assembly when the parts are connected in unitary relation.

Various changes in the shape, size and arrangement of parts may be made to the form of invention herein shown and described without departing from the spirit of the invention or the scope of the following claims.

I claim:

1. In a leveling device the combination of a sleeve-like plug having projections extending from an end thereof, means for attaching said plug to said article to be leveled with said projections biting into said article, an externally screw threaded expandable leveling part mounted upon said plug for sliding therealong, an internally screw threaded tread cap adjustably threaded on said leveling part, and means on said plug and leveling part for expanding said leveling part into lock thread engagement with the cap.

2. In a leveling device for leveling articles such as furniture the combination of a part having means associated therewith for attachment to the article to be leveled, an externally screw threaded leveling part non-rotatably mounted for relative axial sliding upon the first mentioned part, an internally screw threaded tread cap adjustably threaded upon the threads of said leveling part, said leveling part having a portion thereof longitudinally slotted and an internal annular groove about said slotted part of the leveling part, and cam means upon the attaching part first mentioned seated in said groove for expanding the slotted portion of said leveling part into thread locked engagement with said tread cap.

3. In a leveling device the combination of an article attaching part having a lateral extension at the lower end thereof, a sleeve-like bushing having the lower portion thereof vertically slotted and externally screw threaded, said sleeve having a tapered socket to receive therein the extension of said attaching part for axial movement therein for variably expanding the slotted portion of said sleeve, and a tread cap threaded upon the threads of said sleeve.

4. In a leveling device the combination of an article attaching part having an annular expanding flange laterally at the lower end thereof, a sleeve-like bushing having the lower portion thereof vertically slotted and externally screw threaded, said sleeve having an annular socket with a downwardly convergent tapered cross section to receive therein the flange of said attaching part for expanding the slotted portion of said sleeve, and a tread cap threaded upon the threads of said sleeve.

5. In a leveling device the combination of an article attaching plug having an annular laterally extending expanding flange and a central passageway therethrough, an attaching screw in said passageway, a sleeve-like bushing having the lower portion thereof provided with a slot, said bushing being externally screw threaded and the slotted portion being adapted to receive the expanding flange of the attaching part to laterally expand the slotted portion of said bushing, through relative longitudinal movement of the plug and bushing, means to prevent relative rotation of the bushing upon the attaching part, and an adjustable internally screw threaded tread cap upon the threads of said bushing.

6. In a leveling device the combination of an article attaching plug having an annular laterally extending expanding flange and a central passageway therethrough, an attaching screw in said passageway, a sleeve-like bushing having the lower portion thereof provided with a slot, said bushing being externally screw threaded and the slotted portion being adapted to receive the expanding flange of the attaching part to laterally expand the slotted portion of said bushing, means to prevent relative rotation of the bushing upon the attaching part, and an adjustable internally screw threaded tread cap upon the threads of said bushing, said attaching part, bushing and tread cap all being constructed of hard synthetic plastic.
